UNITED STATES PATENT OFFICE.

HENRY E. McGOWAN, OF NEW YORK, N. Y.

SYSTEM OF COOLING FOR CONDENSING STEAM PLANTS.

No. 874,859.

Specification of Letters Patent.

Patented Dec. 24, 1907.

Application filed May 17, 1907. Serial No. 374,156.

To all whom it may concern:

Be it known that I, HENRY E. McGOWAN, a citizen of the United States, residing at New York, in the county of Kings and State 5 of New York, have invented new and useful Improvements in a System of Cooling for Condensing Steam Plants, of which the following is a specification.

My invention relates to cooling system for 10 steam plants and especially condensing steam plants, regardless of whether such plants are used for the development of power for evaporation or for any one of a number of similar uses.

15 The invention consists in providing various structural details whereby certain economies are brought about and functions performed not heretofore operated in conjunction. These objects are obtained by an arrangement of apparatus such as shown in the 20 diagrammatic view forming a part hereof which serves to illustrate one method by means of which the invention may be carried into practice.

25 The hot well A which preferably is plural, or which may contain a plurality of chambers *a, a', a''*, is introduced between the cooling tower B and the condenser C of the engine D. In the base, or suitably connected 30 with the cooling tower B, is a reservoir E connected by pipe F for supplying the condenser C, an extraneous supply being furnished by water pipe G controlled by valve G' actuated by the float G'', suitably placed, 35 for instance, in the hot well and responsive to differences in level of the water in the reservoir with which it cooperates. A circulating or lifting pump H draws its supply from hot well A, by means of pipe H', it being understood 40 that the drawing is simply diagrammatic, as no lift against gravity need be encountered in the supply to pump H. Pipe H'' furnishes the water to the upper part of the cooling tower B. This may be of any 45 convenient form. Any cooling device may be employed in lieu of the tower B shown in the drawing. In one of the cavities or in the hollow wall forming a dam between cavity *a* *a'* is an oil removing apparatus which in the 50 present instance is represented by the device I. This consists of a mat of oil-absorbing material, for instance "excelsior" or wood shavings, through which the water readily flows, leaving the oil behind, and when 55 clogged, this matress-like device may be slightly raised by pulley or device I', thereby

affording a new surface for extracting the oil, which is to be understood is the ordinary cylinder oil coming from engine D, or fatty matters coming from any source in and about the 60 engine room. The boiler J supplies steam to the engine through pipe J' and is fed by the boiler feed system K having pipes K' and K'' leading from the heater K to the boiler J. The fan L or other cooling means employed 65 in connection with the tower is driven by motor M whereas the circulating pump is driven by motor M' and these motors are each controlled by the rheostats R and R' and switches S and S'. These rheostats, 70 while they are independently controllable, may be moved simultaneously and either or both may be automatically controlled as by the thermometric device T, which may serve to operate an intermediate energizing mechanism, such as motor m controlled by reversing switch n of the well known construction. This operates on the worm gear o controlling the rheostats in response to the variation in 75 temperature of the water or contents of tank E. An overflow pipe B' between the tower B and the hot well A is shown at the proper level and in proper relation to each of these elements.

The use and operation of my device will be 80 apparent from the foregoing. Attention may be, however, called to the fact that by use of my invention a comparatively small cooling tower may be employed, because the arrangement is such that the water may be passed through such tower several times as rapidly as it is fed to the condenser C. Heretofore it has been the practice to pass the cooling water for the condenser in a single circuit from the condenser to the cooling 85 tower and back, but in the present device a multiple circulation is provided whereby the water flowing through the tower may be in excess of that furnished to the condenser, an overflow between the tower and supply reservoir a'' which may be a part of the hot well being supplied, as shown in the drawing. Thus we have a multiple water circulation 90 between the hot well and the tower, in combination with a reservoir for supplying the condenser connected with the tower, which is constantly more and more cooled. Over and above this, the hot well is multiple in its structure and the various compartments which may be either separate or parts of a single structure, are made to perform various 95 functions, such for instance as oil separation.

between a and a' and again such for instance as heat insulation as between compartment a and a'' , whereby the former is kept the hotter owing to the multiple circulation to the tower B and from which compartment the boiler feed derives its supply by means of pipe K', as is readily understood, — the hot discharge from the condenser entering the first sections of the multiple well. The boiler feed is supplied with the additional heater K and the extraneous water supply entering the system at or near the condenser is made automatic and responsive to the water levels in some suitable tank connected with the system, as for instance, the hot well or one of its compartments, as shown through the device of the float G'' and valve G' .

In cold weather it is understood that not as much cooling action is necessary through the cooler or fan L, nor is the multiple circulation required to be as vigorous. Therefore, both of these devices may be made to absorb less power from the system. This may be manually regulated or automatically, as shown by the thermometric device T operating to control the motors M and M' or either of them, either directly or through the intermediary of the power arrangement comprising motor m and mechanism o .

It will readily be understood that many of the details may be varied and their arrangement may be altered without departing from the spirit of the invention.

1. claim:—

1. In a cooling system for condensing steam plants, a condenser, a hotwell for receiving the discharge from the condenser, a cooling tower discharging into the condenser, and a multiple water circulation between said hot well and the tower and automatic means for varying the said circulation.

2. In a cooling system for condensing steam plants, a condenser, a hot well for receiving the discharge from the condenser, a cooling tower discharging into the condenser and means for delivering the water from said hot-well to the tower in excess of that furnished to the condenser and an overflow from the tower to the well.

3. In a cooling system for condensing steam plants, a condenser, a hot well for receiving the discharge from the condenser, a cooling tower discharging into the condenser and a multiple water circulation between the said hot well and the tower.

4. In a cooling system for condensing steam plants, a condenser, a hot well for receiving the discharge from the condenser, a cooling tower discharging into the condenser and a reservoir connected to the base of the tower feeding such condenser.

5. In a cooling system for condensing steam plants, a condenser, a hot well for receiving the discharge from the condenser,

a cooling tower discharging into the condenser and a multiple water circulation between said hot well and the tower and automatic means responsive to the temperature in the hot well for varying the said circulation.

6. In a cooling system for condensing steam plants, a condenser, a multiple hot-well for receiving the discharge from the condenser, a cooling tower discharging into the condenser, an overflow from the tower to said hot-well, the hot discharge from the condenser being received in a different compartment than the said overflow.

7. In a cooling system for condensing steam plants, a condenser, a hot well for receiving the discharge from the condenser, means for cooling the water from the hot well, means for supplying the cooled water to the condenser an extraneous water supply for the condenser and means for controlling said extraneous supply responsive to the water levels in the hot well.

8. In a cooling system for condensing steam plants, a condenser, a hot well for receiving the discharge from the condenser, a cooling tower discharging into the condenser, a multiple reservoir connected to the base of the tower feeding such condenser, the hot discharge of the condenser being received in a different compartment than that supplying the condenser.

9. In a cooling system for condensing steam plants, a condenser, a hot well for receiving the discharge from the condenser, a cooling tower discharging into the condenser, a multiple reservoir connected to the base of the tower feeding such condenser, the hot discharge of the condenser being received in a different compartment than that supplying the condenser, and a filter located between the compartments.

10. In a cooling system for condensing steam plants, a condenser, a hot well for receiving the discharge from the condenser, a cooling tower discharging into the condenser, a multiple reservoir connected to the base of the tower feeding such condenser, the hot discharge of the condenser being received in a different compartment than that supplying the condenser, a boiler feed for the system and a separate compartment of the reservoir for supplying such feed.

11. In a cooling system for condensing steam plants, a condenser, a hot well for receiving the discharge from the condenser, a cooling tower discharging into the condenser, the tower receiving its supply from the said hot well and an extraneous water supply entering the system and automatic means for controlling such extraneous water supply responsive to the water levels of the hot well.

12. In a cooling system for condensing steam plants, a condenser, a multiple hot well

for receiving the discharge from the condenser, a cooling tower discharging into the condenser and deriving its supply from one compartment of said hot-well and an over-
5 flow for the hot well connected with another compartment.

13. In a cooling system for condensing steam plants, a condenser, a cooling tower, means for circulating water through such 10 tower, means for causing an air current through such tower in combination with means for automatically varying such circulation.

14. In a cooling system for condensing steam plants, a condenser, a cooling tower, means for circulating water through such tower, means for causing an air current through such tower in combination with

means for automatically varying such current.

15. In a cooling system for condensing steam plants, a condenser, a cooling tower, means for circulating water through such tower, means for causing an air current through such tower in combination with 25 means responsive to the temperature of the water for automatically varying such current.

In testimony whereof I have hereunto set my hand in presence of two subscribing 30 witnesses.
